UNITED STATES PATENT OFFICE.

PETER MACDONALD BURNS, OF SAN FRANCISCO, CALIFORNIA.

WIRE-TWISTER.

1,334,221.

Specification of Letters Patent. Patented Mar. 16, 1920.

Application filed April 23, 1919. Serial No. 292,007.

To all whom it may concern:

Be it known that I, PETER MACDONALD BURNS, a citizen of the United States, and a resident of San Francisco, in the county 5 of San Francisco and State of California, have invented a new and useful Improvement in Wire-Twisters, of which the following is a specification.

My invention relates to devices for twisting 10 ends of wire together and more particularly to a tool of this character for connecting the ends of tie wires on bales, boxes, and all other packages, containers and the like upon which tie wires are used.

15 The principal object of the invention is to provide a simple, inexpensive, and efficient wire twisting tool which will rapidly and effectively connect the ends of tie wires and the like by comparatively few operations of a lever.

20 Further objects are to provide a novel form of wire gripping and twisting member; to provide a simple and efficient ratchet mechanism for driving said member; and 25 to make novel provision for limiting the movement of the operating lever.

With the foregoing in view, the invention resides in the novel construction and arrangement of parts hereinafter described 30 and claimed, reference being made to the accompanying drawings.

Figure 1 is a perspective view showing the invention in use.

Fig. 2 is a side elevation.

35 Fig. 3 is a side elevation.

Fig. 4 is a central, longitudinal section.

Fig. 5 is a front end elevation.

Fig. 6 is a perspective view of the wire gripping and twisting member.

40 Fig. 7 is a perspective of the locking dog of the driving gear.

Briefly speaking, the tool consists of an elongated base 1, a hollow head 2 at the front end of said base, a wire gripping and 45 twisting member 3 mounted in said head, a gear 4 likewise mounted in said head for driving said gripping and twisting member, and a lever 5 serving to actuate said gear; together with numerous novel features of 50 construction, all hereinafter described in detail.

The base 1 may well be in the form of a straight metal bar and its head 2 is preferably formed by two vertical plates 6 secured 55 thereto in spaced relation by screws or other fasteners 7. The front ends of the plates

6 are provided with open throats 8 to receive the wire and immediately below said throats, with forwardly extending toes 9 adapted for passage under the wire to guide 60 the latter into the throats.

On their inner sides, the plates 6 are formed with circular bearing sockets 10 in which the ends of the member 3 are rotatably received, and although said member 65 could well be of any adequate construction, I preferably form the same of two end disks 11, a hub 12 connecting them, and pins 13 extending between said disks to form a 70 pinion for mesh with the gear 4. The disks 11 and hub 12 are provided with open throats 14 of a width equal to the diameter of the wire, while the throats 8, above described, must be at least twice such width in order that the ends of the wire may be 75 twisted together by the member 3, without cutting the wire.

The gear 4 is of the common spur type and meshes with the pins 13, said gear being mounted on a transverse bolt or other 80 form of shaft 15 which extends between and beyond the plates 6. Two links 16 are pivoted at their front ends upon the bolt 15 and may well be tied together by an arched plate 17, and the lever 5 is located 85 between said links, being fulcrumed between its ends to the rear ends of said links as seen at 18. The front end of the lever 5 is provided with a forwardly projecting beveled nose 19 which coacts with the gear 4 90 to rotate the latter when said handle is oscillated. A spring 20, secured to the handle 5 and resting on the tie plate 17 serves to normally throw the nose 19 into engagement with the gear 4, the front end of the 95 lever then bearing against the lower side of said tie plate as depicted in Fig. 4.

The forward movement of the lever 5 and the links 16 is limited by the plate 17 striking the upper edges of the plates 6, at the 100 front ends of the latter, and V-shaped notches 21 may well be formed in said edges to provide flat surfaces for contact with said plate 17. Rearward movement of the links 16 and the lever 5 is checked by contact of the former with the upper edges of the plates 6, at the rear ends of such plates. It is rather important to provide the above 105 described, or other suitable stop means for the lever 5, since the ratio of the gear 4 and the pinion formed by the pins 13 and associated parts, is such as to cause the

movement of said gear by each rearward stroke of the lever, to rotate said pinion one complete revolution. It is thus insured that by moving the lever 5 always to the limit allowed by the stops, the throats 14 will be in register with the throats 8, at the completion of the twisting operation, regardless of the number of twists given the wire.

The lever 5 and gear 4 act as a ratchet mechanism for twining the member 3 and in order to prevent untwisting of the wire on the idle forward strokes of said lever, a suitable dog, such as 22, must be provided. I preferably mount the dog 22 as seen in Fig. 4, that is by providing the lower edge thereof with a notch 23 receiving a pin 24 which extends between the two plates 6. The nose of the dog engages the teeth of gear 4 and its tail is held against the base 1 by a spring 25 secured to the latter. The spring 25 permits rocking of the dog 22 as required and serves also to retain said dog on the pin 24.

In operation, the toes 9 are inserted under the ends of the tie wire and thus guide such ends into the throats 8 and 14. The handle is now moved forwardly to the extent allowed, the nose 19 in the meantime riding idly over the teeth of the gear 4, against the tension of spring 20. The handle is next pulled rearwardly to the full extent allowed, the nose 19 now serving to drive the gear 4 to such an extent as to rotate the member 3 one revolution, thus giving the wire one twist. Three such operations of the lever are usually required to twist the ends of the wire together properly, but more or less twisting may be done if desired. After each operating or rearward stroke of lever 5, the dog 22 holds the gear 4 and consequently the twisting member 3 against retrograde rotation. Since the arrangement of parts is such as to aline the throats 8 and 14 after each operation of the tool, it may be easily removed from the wire.

From the foregoing, it will be seen that I have carried out the objects of the invention in an expeditious manner, and since probably the best results are obtainable from the details disclosed, they may well be followed. However, within the scope of the invention as claimed, numerous minor changes may be made, and obviously any suitable materials may be used.

55 I claim:-

1. In a wire twister, a head having a wire receiving throat, a wire twisting member journaled upon said head and having a throat adapted to register with said first named throat, said wire twisting member being formed as a gear, an operating gear journaled upon said head and engaging said wire twisting member, a lever pivoted upon said head and engaging said second named gear whereby to effect rotation there-

of in one direction, and a spring pressed pawl pivoted upon said head and engaging said second named gear whereby to prevent retrograde movement thereof.

2. In a wire twister, a head formed as a pair of spaced side members each provided with a wire receiving throat, a wire twisting member journaled between said side members and having a throat for registration with said first named throat, said wire twisting member being formed as a gear, a relatively large operating gear pivoted between said side members and meshing with said wire twisting member, a lever pivotally connected with the journal of said second named gear, a tooth on said lever engaging said second named gear whereby to effect movement thereof in one direction when said lever is reciprocated, and means for preventing retrograde movement of said second named gear.

3. In a wire twister, a head having a wire receiving throat, a wire twisting member carried by said head and consisting of a pair of spaced disks, a hub connecting said disks, and pins extending between said disks around said hub, said hub and disks having throats for registration with the throat of said head, a gear carried by said head and meshing with said pins, and means for rotating said gear.

4. In a wire twister, a head, wire twisting means carried by said head, a gear carried by said head for operating said wire twisting means, links pivoted to said head, and a lever fulcrumed to said links and having a nose engaging the teeth of said gear for operating the same when said lever is oscillated.

5. In a wire twister, a head, wire twisting means carried by said head, a gear carried by said head for operating said wire twisting means, links pivoted to said head, a tie plate connecting said links near their pivoted ends and a lever between said links and fulcrumed between its ends thereto, said lever having a nose for engagement with the aforesaid gear to rotate the same when said lever is oscillated, pivotal movement of said lever in one direction being limited by said tie plate.

6. In a wire twister, a hollow head having wire twisting means therein, means for operating said wire twisting means, including a gear in said head and a ratchet lever, a pin extending across the interior of said head, a dog coacting with said gear and having in its lower side a notch receiving said pin, and a spring for said dog acting both to engage said dog with said gear and to prevent movement of said dog from said pin.

7. In a wire twister, a head having side members provided at their front ends with wire receiving throats and below said

throats with tapered toes for guiding the wire into said throats, a rotary wire twisting member between said side members and having a throat for registration with the aforesaid throats, said wire twisting member having gear teeth, a gear between said side members meshing with said gear teeth, a ratchet lever for operating said gear, and a dog between said side members to hold said gear against retrograde rotation and means for limiting the movement of the ratchet lever in both directions.

8. In a wire twister, a head having side members provided at their front ends with wire receiving throats and below said throats with tapered toes for guiding the wire into said throats, a rotary wire twisting member between said side members and having a throat for registration with the aforesaid throats, said wire twisting member having gear teeth, a gear between said side members meshing with said gear teeth, links pivoted to and extending from said side

members, a lever between and fulcrumed between its ends to said links, said lever having a nose for operating said gear when said lever is oscillated, and a dog between said side members for holding said gear against retrograde rotation.

9. In a wire twister, a head having a wire-receiving throat, a wire twisting member carried by said head and consisting of a pair of spaced disks, a hub connecting said disks, pins extending between said disks around said hub and disks having throats in register with the throat of said head, a gear carried by said head and meshing with said pins, and means for rotating said gear, said head having side members provided in their inner sides with circular sockets in which said disks are rotatably received.
